UNITED STATES PATENT OFFICE.

THOMAS E. CONNELLY, OF PITTSBURG, PENNSYLVANIA, ASSIGNOR OF ONE-HALF TO JOHN S. CONNELLY, OF SAME PLACE.

CHEMICAL FIRE-EXTINGUISHER.

SPECIFICATION forming part of Letters Patent No. 317,513, dated May 12, 1885.

Application filed September 3, 1883. (No model.)

To all whom it may concern:

Be it known that I, THOMAS E. CONNELLY, of Pittsburg, in the county of Allegheny and State of Pennsylvania, have invented a new and useful Improvement in Chemical Engines; and I do hereby declare the following to be a full, clear, and exact description thereof.

My invention relates to an improvement in chemical engines or fire extinguishers; and it consists, mainly, in combining with a basket or cage having a cushion-spring for supporting and cushioning a frangible chemical receptacle, a plunger, also provided with a cushioning-spring, whereby the frangible chemical receptacle is effectually guarded against accidental fracture.

I will now describe my invention so that others skilled in the art may manufacture and use the same, reference being had to the accompanying drawings, forming part of this specification, in which—

Figure 1 is a side elevation of my improved chemical engine. Fig. 2 is a vertical sectional view of the same. Fig. 3 is a side elevation, partly in section, of the basket detached. Fig. 4 is an end view of the plunger-head, and Fig. 5 is a side elevation of the same.

Like letters of reference indicate like parts wherever they occur.

In the drawings, *a* represents the body of the engine mounted on a suitable carriage, as shown in Fig. 1.

At the top of the cylinder *a* is the mouth *b*, through which the chemicals are introduced. This mouth is closed by a removable head or screw-lid, *c*, which screws inside of a screw-threaded collar, *d*.

Extending vertically through a suitable opening in the lid or cover *c* is a plunger or piston, *e*, at the lower end of which is a head or disk, *f*, from the edges of which V-shaped knife-edged lugs or arms *e'* extend laterally. This rod or plunger is adapted to be moved up and down in the packing-box *f'*.

Below the lid *c*, inside of the extinguisher, is a removable basket or bucket, *h*, having a perforated bottom and sides, and a bail, *h'*.

Around the upper edge of the basket *h* is a ring or collar, *i*, which rests on a shoulder, *k*, formed on the inner face of the ring or col-

lar *d*, while the body of the basket extends down into the extinguisher.

Inside of the basket *h* is a bottle, *j*, of glass or other frangible material, which contains the acid. This bottle is kept stationary in the basket by means of a spring, *l*, in the bottom of the basket, and a spring, *m*, on the face of disk *f*, which bear on the bottom and top of the neck of the bottle and prevent it from being accidentally broken.

The operation is as follows: The body of the extinguisher is charged in the usual manner; the basket *h* is then placed in position in the mouth of the extinguisher, the hermetically-sealed bottle *j*, containing the acid, is placed therein, and the cover *c* is screwed in the ring *d*. By striking a blow on the top of the plunger *e* the disk *f* descends and breaks the bottle, the lugs *g* serving to split the bottle longitudinally, so that the entire contents thereof shall escape into the basket, and thence, through the interstices or perforations, into the body of the extinguisher. When the charge has been exhausted, the cover *c* is unscrewed, the basket *h* is removed, and the broken glass is emptied therefrom. The extinguisher is then recharged, the basket is replaced, containing another bottle of acid.

The different parts of the engine may be constructed of any suitable materials. I prefer, however, to form the plunger *e* and basket *h* of brass, so as to resist the action of the acid.

The advantages of my invention are that the different parts of the apparatus are easily accessible, and may therefore be prevented from corroding.

The engine is easily charged rapidly without danger of injury to the apparatus or workman, and the bottle or acid-receptacle is protected by the springs from being accidentally broken.

My improved engine may be charged with any suitable chemicals for generating ammoniacal, nitrous, carbonic-acid, or other gases effective in smothering flames.

Having thus described my invention, what I claim, and desire to secure by Letters Patent, is—

In a chemical engine or fire-extinguisher, the combination of a basket or perforated cage having a cushioning-spring arranged in its bottom, a crushing-plunger having a cushioning-spring at its lower end, and an interposed frangible chemical receptacle, substantially as and for the purposes specified.

In testimony whereof I have hereunto set my hand this 29th day of August, A. D. 1883.

THOMAS E. CONNELLY.

Witnesses:

JOHN S. KENNEDY,

THOMAS W. BAKEWELL.
